FILTER FOR INVERTED PUMPS

Roy L. Chenault, Oakmont, Pa., assignor to Gulf Research & Development Company, Pittsburgh, Pa., a corporation of Delaware

Application December 10, 1942, Serial No. 468,583

5 Claims. (Cl. 103—180)

This invention relates to a filter for inverted pumps which is effective to supply some of the pumped liquid, freed from sand or other abrasive, to the region of the pump packing to flush and lubricate the same, thereby to minimize erosion and deterioration of the packing and, consequently, to maintain the volumetric efficiency of the pump.

In pumps of the inverted type a reciprocating barrel works upon a fixed, hollow plunger which is valved to prevent return flow to the well. Upon upstroke, the well liquid is drawn into and through the plunger for discharge past a valve in the barrel upon the following downstroke. Thus, in continued reciprocation of the barrel the liquid is pumped to the surface.

Pumps of this type employ packing to seal the clearance space between the plunger and barrel, but where sand is carried along with the pumped liquid, as for example where sandy oil is encountered, the resulting abrasion and wear on the packing cause rapid deterioration. Replacement is laborious and expensive as well as time-consuming.

These disadvantages are avoided in the usual reciprocating plunger type of pump by the provision of filtering ports through which some of the oil being pumped passes from the bore of the plunger into the clearance space in the vicinity of the packing, the oil in the plunger being under tubing pressure. The application of a filter and sand scraping cup to the high pressure side of the pump packing is complicated, in the case of an inverted pump, however, because the tubing pressure is not applied to the inner bore of the plunger, the oil being drawn therethrough, with the consequent tendency to draw sandy oil into the clearance space which communicates with the bore of the plunger. The condition which is sought to be avoided is thereby aggravated, instead. Filtering of the liquid supplied to the region of the packing must be accomplished under higher pressure than exists in the plunger.

The present invention, therefore, has for its principal object the provision of a filter for inverted pumps wherein in both directions of reciprocation of the barrel filtered liquid is admitted to the clearance space around the packing to flush the same of abrasives which cause wear and deterioration.

A further object is to provide means for supplying filtered liquid under pressure to the clearance space of an inverted pump by bypassing the same around the scraper at the high pressure side of the pump packing.

Other and further objects and advantages of the invention will be manifest from the following description and drawing wherein:

5 Figure 1 is a view, partly in section, of an inverted pump assembly incorporating the filter arrangement of this invention.

10 Figure 2 is an enlarged vertical sectional view of the plunger.

15 Figure 3 is a transverse sectional view taken along line 3—3 of Figure 2.

20 Figure 4 is a vertical sectional view, taken through the lower scraper ring and filter of a modified form of the invention.

25 Figure 5 is a transverse sectional view, along line 5—5 of Figure 4.

Referring more particularly to the drawing:

30 A string of tubing 10 which extends into the well has a short reducing nipple 11 secured to its lower end by a threaded coupling sleeve 12. The upper end 13 of the nipple supports a seating member 14 which carries friction cups or rings 15 in sealing contact with the wall of the nipple to prevent leakage and to confine the flow of liquid from the well into the pump plunger 16 through a connecting pipe 17.

35 A pump barrel 18 works upon the plunger and on downstroke discharges through an upwardly opening check valve 19 which is confined by a cage from which the sucker rod connection 20 extends. At its lower end the pump barrel mounts a sleeve 21 which is formed with an inturned abutment to retain the plunger within the barrel in installation of the pump and to bear upon the seating member 14 to secure the same in the nipple 11 in the final assembly, whereafter the limit of the barrel stroke is determined by travel of the abutment between the lower end of the plunger and upper surface of the seating element 14.

40 As shown more particularly in Figure 2, the plunger comprises a tubular body member which contains a ball check valve 22 resting upon seat 23 which is retained between the threaded sections 24 and 25 of the plunger barrel. The section 25 of the plunger is of reduced external diameter throughout a portion of its length and receives a plurality of pressure holding cups 26 with intervening spacers 27, the packing assembly being held in position by a threaded retainer

45 sleeve 28 which, additionally, clamps a sand scraper ring 29 spaced from the assembly of packing rings by a sleeve 30. A similar but oppositely directed scraper ring 31 above the assembly of packing rings is retained by the annular shoulder 32 formed on a tubular sleeve 33

which is secured to the plunger section 24. A plurality of ducts 34 in the sleeve 33 communicate with the clearance space between the plunger and its barrel above the upper scraper ring and similar ducts 38 below the sand scraper ring convey liquid through a cylindrical filter 36, woven wire screen 37 and ports 35 to the annular space extending from the upper pumping ring to scraper rings 31. Below the lower scraper ring a series of ducts 39 extend to an enlarged annular space 40 to a series of longitudinally extending passages 41 which are milled or otherwise formed in the body of the plunger part 25 and which communicate with a space above the lower scraper ring in which a cylindrical filter 41 is retained by woven wire screens 42. Ducts 43 lead from such space to the exterior of the plunger between the lower backing rings and the lower scraper ring 29.

In the modified form of invention shown in Figure 4 the passages 44 are shown as formed in the surrounding sleeve 47 rather than in the plunger body. In both forms of the invention, however, the liquid to be filtered and discharged into the clearance space flows through passages which by-pass the lower sand scraper, the latter being at the high pressure side of the packing. The passages terminate above and below the scraper cup and have no communication with the bore of the plunger as a consequence of which liquid forced through them is under higher pressure than that existing within the plunger.

On upstroke of the pump valve liquid is drawn from the well through the seating element 14 and pipe 17 past check valve 22 in the fixed plunger. At the same time liquid around the plunger flows through the ducts 39, filter 41 and communicating ducts 43 into the clearance space in the region of the packing 26. This liquid being filtered contains no abrasive which will cause erosion of the packing and its subsequent rapid deterioration.

On the succeeding downstroke of the pump barrel the upper scraper ring is expanded to contact with the barrel and since the check valve 22 is closed, pressure within the plunger causes liquid above the valve to pass outwardly through the ducts 38 and filter 36 to be discharged through orifice 35 into the space below the upper sand scraper, thereby in turn to discharge sand-free liquid into the clearance in which the packing rings 26 operate. Thus, it will be apparent that a part of the oil or other liquid supplied to the pump is filtered and discharged to the space between the plunger and barrel in region of the packing rings in both directions of reciprocation, such filtered liquid serving to flush the space and lubricate the packing rings, and to equalize pressure across the scraper rings. As a consequence erosion and wear are minimized and high volumetric efficiency of the pump is maintained without requiring frequent replacements of parts which would otherwise be subjected to abrasion.

What I claim is:

1. In an inverted deep well pump, a valved plunger and a barrel reciprocable thereon, packing in the clearance space between said plunger and barrel, sand scraper means in advance of said packing, a duct opening into the clearance space above and below said sand scraper means, and a filter in said duct.

2. In an inverted deep well pump, a valved plunger and a coating reciprocating barrel, packing in the clearance space between said

plunger and barrel, sand scraping means above and below said packing, means for delivering filtered well liquid to the space between said sand scraping means and said packing, said means comprising a duct communicating with the space exterior to the plunger on opposite sides of said lower sand scraper, a filter in said duct, a duct for delivering well liquid under pressure to the space exterior to the plunger below the said upper sand scraper, and a filter in said last named duct.

3. In an inverted deep well pump, a fixed, tubular plunger and a coating, reciprocating barrel, a valve in said plunger to prevent return flow of liquid, packing means carried by said plunger to provide a seal against the wall of said barrel, a lower sand scraper carried by said plunger, a passage circumducting said lower sand scraper and terminating exteriorly of said plunger, filter means in said passage, a second sand scraper carried by said plunger at a point above the said valve therein, a passageway providing communication between the exterior and the bore of said plunger, and a filter in said passageway, whereby upon upstroke of said barrel liquid under pressure is discharged through said first filter into the clearance space between the upper and lower sand scrapers, and upon downstroke liquid under pressure above said plunger valve is discharged from the plunger bore, through said second filter, and also into the clearance space in the region of the packing.

4. In an inverted deep well pump, a fixed tubular plunger and a barrel reciprocable with respect thereto, the barrel and plunger being mounted in a tube string through which liquid is admitted from the well to the interior of the plunger, packing carried by the plunger and sealing the clearance space between it and the barrel, check valves in said plunger and barrel opened successively in reciprocation of the barrel for lifting well liquid through the plunger and discharging it into the tube string, sand scraper means carried by said plunger above and below the packing, a passageway circumducting the lower sand scraper and terminating at the exterior of the plunger for admitting well liquid from below the lower sand scraper under pressure in downward reciprocation of said barrel and discharging the same above said lower sand scraper, a filter in said passageway to remove abrasive from the liquid so delivered to the region of the packing, a passageway below the upper said sand scraper communicating with the interior of said plunger above the valve therein, and a filter in said passageway to remove abrasive from the liquid delivered under pressure within said plunger in upstroke of the barrel, thereby on successive strokes of the barrel to discharge filtered liquid to the clearance space in the region of the packing for flushing the same.

5. In an inverted deep well pump, a valved plunger and a barrel reciprocable thereon, packing in the clearance space between said plunger and barrel, scraping means spaced from said packing, a duct for conveying liquid to the clearance space in the region between the scraping means and packing, from the clearance space on the opposite side of said scraping means, and a filter for removing abrasive particles from liquid delivered to the region between said scraping means and packing.
